DESIGN FOR A DRESS

Louise Fenaroli, Astoria, Long Island, N. Y.

Application November 17, 1937, Serial No. 72,941

Term of patent 3½ years

To all whom it may concern:

Be it known that I, Louise Fenaroli, a citizen of the United States, residing at 3033 32nd Street, Astoria, Long Island, in the county of Queens, city and State of New York, have invented a new, original, and ornamental Design for a Dress, of which the following is a specification, reference being had to the accompanying drawing constituting a part thereof.

Fig. 1 is a front view of the dress.

Fig. 2 is the rear view of the dress as shown in Fig. 1.

The characteristic feature of the dress resides in the scallops sewn within the seams near the bottom of the skirt in combination with the waist portion having arcuate seams at the lower front waist portion with radiating pleats and similar harmonizing pleats upon the sleeves.

I claim:

The ornamental design for a dress substantially as shown and described.

LOUISE FENAROLI.
